UNITED STATES PATENT OFFICE.

LOUIS RUGAARD, OF SAN BRUNO, CALIFORNIA, ASSIGNOR OF ONE-HALF TO ERNST A. BOHM, OF SAN BRUNO, CALIFORNIA.

STOVE.

1,042,973.

Specification of Letters Patent. Patented Oct. 29, 1912.

Application filed October 26, 1911. Serial No. 656,986.

To all whom it may concern:

Be it known that I, Louis RUGAARD, a citizen of the United States, residing at San Bruno, in the county of San Mateo and State of California, have invented certain new and useful Improvements in Stoves, of which the following is a specification.

My invention relates to improvements in stoves.

The object of my invention is to provide a device whereby pots or cooking utensils of various sizes and shapes placed on a stove or range on a steamer or sailing vessel may be prevented from upsetting or sliding from the stove or range on account of the rolling or rocking of the vessel during a voyage.

My invention consists of a frame having certain parts and combinations of parts shown in the accompanying drawings, described in the following specification and claimed in the appended claims.

In the drawings Figure 1 is a plan view of my device, showing it attached to the top of a stove parts of said device herein-after mentioned being illustrated in section. Fig. 2 is a perspective view of a portion of the device, the said view being broken. Fig. 3 is a sectional view of one of the supports of said device having a locking member as hereinafter described. Fig. 4 is a detail view of the sliding locking plate hereinafter mentioned. Fig. 5 is a detail of the upper portion of one of the posts containing said locking plate.

In the drawings, 1 represents the top of a stove to which my said device is secured, the said device or frame having two rear supports or posts 2 and 3 and two front supports or posts 4 and 5. On said supports are placed a front horizontal bar 6 and a rear horizontal bar 7, said bars running longitudinally, and said posts also support transverse bars 8 and 8, said transverse bars running endwise to said bars running longitudinally. By said bars 6 and 7 are supported interchangeable bars 9 having tongues 10 fitted to enter slots 11 in said bar 7, and at the opposite end having slots 12 engageable with grooves 13 formed between transverse ribs facing inwardly in the said bar 6. The ends of the rear bar 7 rest in vertical recesses 14 in posts 2 and 3, and midway said bar 7 is provided with a bent portion 15 projecting inwardly so as to surround the

inwardly projecting portion of a stove pipe or smoke stack 16 as shown.

The two end bars 8 are supported respectively in vertical recesses or slots 17 in posts 2 and 4, and vertical recesses or slots 17 in posts 3 and 5. The front bar 6 is supported by placing one end in a socket 18 in the post 4 and the other in a recess 19 in the post 5. The said front bar 6 is held from upward movement by a slide 20, and the slide 20 is held in place by a press plunger 21 penetrating a finger hole in said slide as shown in Fig. 3, the plunger being resiliently supported by a spring 22, and the spring being held in place in its lower position by a plug 23, said parts being shown in the chambers and seats therefor in post 5 as illustrated in Fig. 3. The slide 20 has a groove 24 in the lower portion thereof, which slides upon the head of plunger 21 when the slide is drawn out, and by the downwardly curved end of said groove, the slide 20 is kept from withdrawal from the undercut grooves 25 in post 5, wherein the beveled longitudinal edge of the said slide 20 is supported and is slidable.

Holes 26 in the interchangeable bars are provided so that said bars may be hung on hooks thereby when not in use and also to reduce the weight of said bars, the hooks 27 penetrating the said holes in the hanging of the bars.

A handle 27 is provided for the front of the frame, whereby the cook may support himself during an excessive rolling of the vessel, the handle being secured by brackets 28, which the ends thereof penetrate, the said brackets having inwardly projecting bars 29, having reduced threaded ends 29' penetrating bar 6 and secured by nuts as 95 shown.

Pots 30 represented by dotted lines in Fig. 1 are shown to illustrate the manner of their support by engagement with the sides of the fixed and interchangeable bars as described, including short bars 31, each of which is also provided with a slot 12, whereby each short bar is solely supported by engagement with one of grooves 13 in bar 6.

The short bars 31 enable a restricted area of the surface of the range to be used, leaving the wider space beyond their inward ends for use for cooking utensils having larger dimensions than those intended to be supported thereby, besides said short bars 110

can be rapidly adjusted as they are solely supported by bar 6.

I claim:

1. In combination with a stove a frame 6 consisting of a plurality of vertical posts, one of said posts being secured at each of the corners of said stove, transverse bars extending between and supported by the upper portions of said posts; a bar having 10 a plurality of apertures extending through its sides, and extending longitudinally between and supported by the posts on one side of said stove, and a bar having a plurality of vertical grooves in one of its sides 15 extending longitudinally between and supported by the posts on the opposite side of said stove, and a plurality of interchangeable bars having ends provided with tongues movably penetrating said apertures and 20 having in proximity to their opposite ends downwardly opening vertical slots movably engaging said grooves.
2. In combination with a stove a frame 25 consisting of a plurality of vertical posts, one of said posts being secured at each of the corners of said stove, transverse bars extending between and supported by the upper portions of said posts, a bar having a plurality of apertures extending through 30 its sides, and extending longitudinally between and supported by the posts on one side of said stove, a bar having a plurality of vertical grooves in one of its sides extending longitudinally between and supported 35 by the posts on the opposite side of said stove, and a plurality of interchangeable bars having ends provided with tongues
- movably penetrating said apertures and having in proximity to their opposite ends 40 downwardly opening vertical slots movably engaging said grooves, and a plurality of interchangeable bars having in proximity to one of their ends downwardly opening vertical slots slidably engaging said grooves.
3. In combination with a stove a frame 45 consisting of a plurality of vertical posts, one of said posts being secured at each of the corners of said stove thereto, transverse bars extending between and supported by the upper portions of said posts, and bars running longitudinally with said stove and supported by the upper portions of said posts, and bars between said transverse bars and 50 removably supported by said bars running longitudinally.
4. In a stove, in combination, a post projecting upwardly at one of the front corners of the stove and having a vertical recess extending downwardly from the upper end of said post, a slideway in the upper end above 55 said recess and extending longitudinally with the stove and a slot extending downwardly from said slideway and opening inwardly in alignment with said slideway, a spring-pressed plunger in said recess, a slide 60 in said slideway having an opening, said opening being penetrable by said plunger, and a bar having an end seatable in said slot.

In testimony whereof I affix my signature in presence of two witnesses.

LOUIS RUGAARD.
